CUTTING MACHINE FOR PAPER AND THE LIKE

Application filed December 16, 1925. Serial No. 75,846.

This invention has reference to improvements in means of effecting the reciprocating or rocking movement of the yoke or so-called saddle employed in connection with paper cutting machines and the like for the delivery or throwing off and the determining of the cutting position of single or superimposed sheets of paper, card-board or the like, and it is intended to make provision whereby all the various movements and adjustments of the saddle and the operating parts thereof may both be performed automatically as well as partly automatically and partly manually, or entirely by manual operation in the discretion of the operator and in accordance with the requirements of the material and of the working conditions. In view thereof it is a further object of this invention to considerably increase the efficiency of machines of this kind, both as regards the output and the number of cuts to be performed in a minute and the exactness of operation and in particular of the cut and to further increase the adaptability and the ease of manipulation of such machines and the yield thereof, so as to amount to a multiple of the output produced with machines of the previous art not provided with similar arrangements. In connection therewith it is a further object of the invention to facilitate the manipulation of such machines for ordinary single cuts with automatic arresting of the knife in its highest position.

These and other objects of the invention will appear from an inspection of the drawings and from the specification illustrating by way of example an embodiment of the principles of the invention, in which:

Fig. 1 is a plan view of the improved machine,

Fig. 1a is an enlarged elevational detail partly in section of the reversing gear and conical coupling, the view being taken on line C—D of Fig. 1b,

Fig. 1b is a top plan detail of the reversing gear and its associated parts, the reversing gear per se being shown in horizontal section on the line A—B of Fig. 1a.

Fig. 1c is a diagrammatic view of the ar-

rangements of the gear wheels of the reversing gear taken on the line G—H of Fig. 1b,

Fig. 1d is a diagrammatic view showing the other wheels of the reversing gear in engagement with each other,

Fig. 2 is an elevational view of the complete machine,

Fig. 2a is an enlarged vertical sectional view through the saddle wheel, coupling and adjacent parts,

Fig. 3 is an enlarged elevational detail for the setting lever for the saddle with adjoining parts.

Similar characters of reference are employed in all of the above described views to indicate corresponding parts.

The invention will be described with reference to the drawings, and with reference to its operation in connection with the manipulation and cutting of a staple of sheet material 35 which is supported on the table 34 and is fed by the feeder or saddle 33 reciprocably mounted on the table 34. A motor engine 1 or the like may be provided for the actuation of the different moving parts of the machine. The fly wheel 2 which is operated by the motor 1 and is preferably provided with the usual friction coupling or the like is connected to the pinion or gear wheel 3 engaging with the gear wheel 4 from which by way of the gear wheels 5, 6, shaft 10, clutch coupling 9 and worm gear 7, 8, and the shaft 11 of the worm wheel 8 the feeding crank 12 which is secured to the shaft 11 may be operated. The crank pin 13 provided on the crank 12 is adapted to engage from below with a longitudinal slot of the rocking arm 14 which oscillates on the stud 15 provided on the supporting frame 16. The rotation of the crank arm 12 causes the rocking arm 14 to be rocked, and its oscillating movement is transmitted by means of the rod 17 to the disc 18 (Fig. 2). By means of the hand wheel 19 and the screw-threaded spindle 20 which are displaceably mounted on the rocking arm 14 and are connected to the pitman rod 17 the point of operative engagement of the rod 17 with the rocking arm 14 may be changed, so that the amplitude of oscillation of the rod 17 may be varied from a

90
95
100

large amplitude down to zero. The extreme positions of the rocking arm 14 are indicated in the drawings partly by dotted lines. The disc 18 to which the rod 17 is connected is 5 coupled by means of clutch rollers 21 or by equivalent means to the freely rotating disc 22 in such a manner that the disc 22 will only be rotated by the disc 18 in one direction of rotation. The disc 22 by means of studs or 10 bolts 23 transmits its rotation to the friction cone 24. The discs 18 and 22 and the friction cone 24 are loosely mounted and rotatable on a stud or shaft 86 which is secured in position by the table 34 and the support 87. The 15 shaft 86 is longitudinally bored for the reception of the adjusting pin 29 and for securing the parts in the adjusted position an adjusting nut 28 is provided at the end of the adjusting pin 29, the said nut 28 resting against the shaft 86 and being preferably 20 connected thereto by means of the setting pin 28a which engages with an annular groove of the shaft or stud 86 and with a suitable opening of the nut 28.

25 In order to make sure that the rotation of the freely rotating disc 22 will take place in one direction only, the disc, besides relying upon the operation of the clutch rollers 21, may be provided with a braking disc or ring 33 87' which is rigidly connected thereto. The braking ring 87' is adapted for engagement with the braking member 88 which is connected to the table 34 by means of the screw-bolt 89 and may be regulated and adjusted by 35 means of the set screw 90, as clearly shown in Fig. 1 of the drawings.

The friction cone 24 may be raised and lowered by means of the hand lever 25 with lever arm 25a, connecting rod 26, lever 27 40 and the adjusting nut 28 with screws 28a and setting bolt 29 above referred to. By this means the friction cone will become engaged and respectively disengaged with the quickly rotating wheel 30 intended for the operation 45 of the saddle 33, the lowering of the friction cone in the exemplification shown in the drawings causing it to become engaged with the wheel 30, while by the raising of the friction cone 24 it is disconnected therefrom. By the rotation of the hand lever 25, so as to cause it to assume, for instance, the 50 position indicated at I in Fig. 3 of the drawings the gear wheel or worm wheel 77 may be engaged with the gear wheel 79 secured to the saddle wheel 30, as more particularly 55 hereinafter described. The saddle wheel 30 will thereby be operated by the gear wheel or worm wheel 77. By means of wire rope 31 which is passed over the guide rollers 31a 60 and is tightened by the tensioning screws 32 the rotation of the saddle wheel 30 is transmitted to the saddle 33 carrying the screws 32 so that the saddle 33 may be reciprocated upon the table 34.

65 Inasmuch as the feeding of the sheets

should only take place, while the knives and the press-beam which are not shown in the drawing have assumed the position above the staple 35 with the knife operating crank 36 and the pull-rod 37 for connection with the knife disposed so as to substantially correspond to the dead-center position of the crank arm, as shown in Fig. 2 of the drawings, the feeding movement will have to be commenced at this moment and it should be 70 terminated as soon as the press-beam has become engaged again with the staple. This object may be attained by correspondingly adjusting the rate of transmission of the driving wheels 3, 4, 5, 6 and by the fact that the 75 operation and the arresting of the feeding gear will be respectively effected at the proper times. This adjustment and proportioning of the feeding movement is effected in the 80 following manner:—To the knife-operating crank 36 the cam 38 is rigidly connected which is in engagement with the roller 39 on the two-armed lever 51 which is thereby 85 rocked on its pivot 40 and by means of the pitman-rod 41, and the link 41a operates on the two-armed lever 42 which is rocked on its pivot 43, causing the cam or roller 44 to be moved away from the path of the projection 46 of the worm wheel 7 contrary to the action of the spring 45. The two-armed 90 lever 42 with the cam roller 44 and the spring 45 are mounted on the forked lever 47 which latter is rotatably disposed on the pivoting stud 48 mounted on the support 16. Now, the clutch or coupling member 9 is axially 95 displaceable on the shaft 10 and is provided with an annular groove in which the stud 49 of the forked lever 47 is adapted to engage, so that by the rocking of the forked lever 47 on its stud 48 the coupling member 9 may be 100 caused to be engaged and respectively disengaged with the corresponding indented coupling member of the wheel 7, the wheel being loosely mounted on the shaft 10. The spring 50 surrounding the shaft 10 tends to 105 keep the coupling constantly in the engaging position. As soon, however, as the cam roller 44 is forced against the projection 46 of the wheel 7, the coupling is disengaged. In consequence of the lateral displacement of the 110 roller 44 by the operation of the cam 38, the double lever 51, the link members 41, 41a and the two-armed lever 42, the roller 44 becomes disengaged from the projections 46 (as clearly shown in Fig. 1 of the drawings) 115 and the spring 50 causes the coupling to be engaged and the feeding movement may then proceed as hereinbefore described. After a full rotation of the wheel 7 its projection 46 is again engaged with the roller 44 which 120 has been forced back to its normal position by the spring 45, as soon as the cam 38 has become disengaged from the roller 39 and the two-armed lever 51 with the corresponding link members 41, 41a and the two-armed lever 125.

42 have all been rocked back by the action of the auxiliary pulling spring 52. The clutch 9 is now disengaged and the feeding movement has been terminated and the cutting of the staple or of the sheets may now be proceeded with.

After the saddle 33 has assumed its extreme forward position, so that the entire length of the staple of sheets has been progressively and intermittently fed forward, as appears from Fig. 1, of the drawings, the stopping member 53 which is secured to the saddle 33 is forced against the arresting screw 54 mounted on the two-armed lever 55 which is thereby oscillated on its stationary pivoting stud 56 and which by means of the pitman-rod 57 connected thereto and linked to the forked lever 47 causes the disengagement of the clutch 9, as hereinbefore described. The said stopping member 53 of the saddle 33 is forced simultaneously against the stopping screw 58 on the two-armed lever 59 adapted to rock on the stationary pivoting stud 60 and operatively connected to the bar 61 which is thereby withdrawn. By the movement of the bar 61 the arresting lever 62 with the roller 69 is raised and the compression spring 63 becomes operative to withdraw the shipping or engagement rod 64 which has been arrested by engagement with a recess or a stud of the arresting lever 62. The spring 63 acting upon the rod 64 rocks the coupling lever 65 on its stationary pivoting stud 66 and causes the friction coupling of the fly wheel 2 to be disengaged, so that the knife and the press beam, not shown in the drawings, are arrested in their uppermost position, while the wheels 3, 4, 5, 6, the shaft 10 and the clutch member 9 continue their rotation with the fly wheel 2 and without the worm wheel 7. The auxiliary tensional spring 67 returns the two-armed lever 59 and the auxiliary tensional spring 68 returns the two-armed lever 62 to their normal positions.

With the instrumentalities above described an automatic feeding movement of the staple is produced after each cut and the cutting takes place automatically at the end of the feeding movement and the knife and press beam are automatically operated from the machine which is continuously moving and becomes respectively engaged with the feeding and cutting means so that the entire operation of the machine will be carried on automatically. As regards the feeding movement which is produced by the engagement of the saddle wheel with the friction cone or coupling member 24 and the rotation of the saddle wheel 30 by the worm wheel 77, three different kinds of feeding movement of the staple may be produced, viz:

1. With the friction cone 24 and the worm wheel 77 both in their middle position the saddle wheel 30 with the gear wheel 79 are

disengaged and the saddle movement may be rapidly effected by hand.

2. With the coupling cone 24 in engagement with the wheel 30 and the worm wheel 77 disengaged from the gear wheel 79 the feeding of the saddle may be entirely or partially effected by automatic means.

3. With the coupling cone 24 out of engagement with the wheel 30 and the worm wheel 77 in engagement with the gear wheel 79 of the wheel 30 the reciprocation of the saddle 33 is effected automatically, while the fine adjustment may be effected by hand.

It therefore appears that the exactness of the cut and the adjustment of the staple may be easily controlled by a judicious operation of the friction cone 24 and of the worm wheel 77 of which the friction cone is operated by the hand lever 25, while the swingingly mounted worm wheel 77 the driving shaft of which is adapted to be rocked at the ball joint 76 and is journalled in the sliding support 77a may be thrown into engagement with the gear wheel 79 by the operation of the hand wheel 81 or by equivalent means, or by the lever arm 25a which is rigidly secured to the hand lever 25 and is connected to the sliding support 77a. The hand wheel 81 is to be employed for the operation of the worm wheel 77 and of the saddle wheel 30 by hand, when the friction cone 24 is disengaged, while the arrangement of the lever arm 25a may be such that the driving of the saddle wheel 30 may be alternatingly produced either by the rocking member 14 or by the worm wheel 77, or the intermittent movement of the saddle wheel 30 produced by the rocking member 14 and the engagement of the friction cone 24 may be changed into a continuous movement by engagement with the worm wheel 77 with a corresponding adjustment of the hand lever 25. In the position of the hand lever 25 indicated at I the worm wheel 77 is engaged, while the friction cone 24 is disengaged from the wheel 30, and in the position III of the hand lever 25 the friction cone 24 is engaged and the worm wheel 77 is disengaged. In the middle position II both the friction cone 24 and the worm wheel 77 are disengaged from the saddle wheel 30.

The driving of the worm wheel 77 in both directions, so as to produce a continuous rapid movement of the gear wheel 79 and of the saddle wheel 30 in both directions, is effected from the sprocket wheel 71 which may be operated from the flywheel 2 by the gear wheels 3, 4. From the sprocket wheel 71 the shaft 74 is operated by the chain drive 72 and sprocket wheel 73. Upon the shaft 74 the reversing gear 75 is arranged which is connected to the shaft of the worm wheel 77 by a ball joint or the like 76, so that by the operation of the hand wheel 81 or of the lever arm 25a, as above described, the chain drive with the reversing gear may be operatively

engaged and disengaged with the gear wheel 79. This reversing gear and its associated parts are shown on an enlarged scale in Figs. 1a to 1d. The reversing gear 75 includes five gear wheels 75a, 75b, 75c and 75c'. The wheels 75c, 75c' and 75d are mounted on the shaft 76 and rigidly connected to each other while the wheels 75a and 75b are loosely mounted on the shaft 74. The conical coupling 75e is keyed to the shaft 74 and is adapted to be engaged with either of the wheels 75a or 75b to control the direction of rotation of the complete reversing gear. By means of a hand lever 78 which is operably mounted on the casing of the reversing gear and operably associated with the conical coupling 75e through the instrumentality of a spring controlled pivot 78' the entire reversing gear 75 may be so adjusted that it will either produce right or left hand rotation of the worm wheel 77. This is attained in that the wheel 75d directly drives the wheel 75c whereby a left hand rotation of the worm 77 is produced while in the other position of the friction cone 75e the wheel 75a drives the wheel 75c over the intermediate wheel 75d. A right hand rotation of the worm 77 is thereby produced. By a more or less heavy pressure on the hand lever 78 due to the friction cone 75e the speed of rotation of the worm wheel may be varied depending on the strength of the said cone or friction clutch. When the lever 78 is released it is brought by the spring of the action of the pivot 78' to its central position whereby the reversing gear 75 runs idle and the worm wheel 77 is stopped.

With the roller 69 in the position I of Fig. 1 of the drawings the arresting lever 62 is raised out of engagement with the spring-actuated coupling rod 64 by the engagement of the stop 53 of the saddle with the stop 58 on the lever 59. In the position indicated at II in Fig. 1 of the drawings the roller 69 on the lever 62 becomes engaged with the cam or eccentric disc 70 rigidly secured to the crank arm 36 of the knife shaft. In the highest position of the knife the cam 70 by means of the lever 62 causes the operation of the spring-actuated rod 64 and the disengagement of the friction coupling of the fly wheel 2 and the arresting of the knife and of the press beam. In this position corresponding to the position II of the roller 69 the feeding is effected automatically and the machine is automatically arrested after each cutting operation. If it is desired to have a repetition of the feeding movement before the new cut is effected, the roller 39 which is operatively connected to the lever 51 and which is itself operated upon by the cam 38 on the knife shaft is moved by manipulating the handle indicated in the drawings in the direction of the arrow, thereby causing the feeding movement to be effected by the operation of the clutch 9. By this means it is possible

after each cut to produce corrections of the feeding distance and eliminate irregularities thereof which may have been caused by irregularities of pressure or by other means, and it is also possible after each cut to cause the feeding to be effected in several steps, so that any feeding distances required even above the maximum normal feeding length may be produced by the machine of this invention.

The engagement and disengagement of the driving means for the knife and of the press beam by hand may be effected by operating the hand lever 82 by means of which, when the lever 82 is set for engagement, the tension rod 64 is moved forward, so that the arresting lever 62 may become engaged therewith and the friction coupling of the fly wheel becomes operated. When the friction coupling is disengaged, the rod 61 is forced back by the hand lever 82, the arresting lever 62 is raised out of engagement and the spring 63 on the rod 64 becomes active and causes the disengagement of the friction coupling of the flywheel 2 by means of the lever 65.

With the clutch member 9 disengaged and with the friction cone 24 in the inoperative position the saddle may be moved at a uniform rate in both directions by means of the machine by merely operating the reversing gear 75 and swinging the worm wheel 77 into engagement with the gear wheel 30, the hand lever 25 being then in the position I. This movement of the saddle is particularly important when the staple is put in position or inverted or otherwise handled.

In order to operate the saddle entirely by hand, a hand wheel 80 is secured to the saddle wheel 30 (Fig. 2) and the adjustment of the saddle by hand may be effected by operating the worm wheel 77 by means of the hand wheel 81 and swinging it into engagement with the gear wheel 79. The position of the saddle 33 is indicated on the saddle wheel 30 by a graduation cooperating with an index finger 85 on the table 34 or the indicating members may be reversely arranged.

It is therefore possible by means of the machine to obtain four different forms of operation, that is to say, 1, the automatic feeding of the staple after each cut with a continuous movement of the knife and press-beam; 2, automatic feeding of the staple with automatic arresting of the machine after each cut in the position II of the roller 69; 3, reciprocation of the saddle by means of the machine without operation of the knife, while the staple is being prepared or reversed; 4, operation of the saddle entirely by hand. By this means the efficiency of the machine for the cutting of paper, card board and the like is greatly increased.

The machine has been described and shown in its preferred embodiment by way of exemplification only, and it should, of course, be understood that it is susceptible of various

modifications and changes in the discretion of the operator to more fully adapt it to varying conditions of application and without deviating from the spirit and scope of the invention as particularly set forth in the appended claims.

The essential features of the invention reside in the facts that both the staple feed as well as the cutting means may be operated both independently of as well as in combination with each other and that the feeding movement takes place during the complete or approximate stopping of the operation of the cutting means, all the manipulations being effected either by machinery or by manual operation or by a combination thereof. The invention is, moreover, evidently applicable to the cutting of other sheet material and of piles and staples thereof besides paper, card board and the like.

I claim:—

1. In a cutting machine in combination, a support, a reciprocable feeding member on the support for the material, coupling means on said support and operably connected with the feeding member, a prime motor, an adjustable rocking member operatively connected to the prime motor and to said coupling means, additional operating means for said feeding member, engageable and disengageable therewith independently of said rocking member, and cutting means for the material.

2. In a cutting machine in combination, a support, a reciprocable saddle on the support for the material, coupling means on said support and operably connected to the saddle, a prime motor, an adjustable rocking member operatively connected to the prime motor and to said coupling means, a clutch intermediate the prime motor and the rocking member, cutting means for the material, operating means for said cutting means engageable with the prime motor, and means on the operating means for the cutting means operatively engageable with the clutch and adapted to move the same into operative position substantially during the inoperative position of the cutting means.

3. In a cutting machine in combination, a support, a reciprocable saddle on the support for the material, coupling means on said support and operably connected to the saddle, a prime motor, an adjustable rocking member operatively connected to the prime motor and to said coupling means, additional operating and feeding means operatively connected to the prime motor and manually engageable and disengageable with the saddle, a clutch intermediate the prime motor and the rocking member, cutting means for the material, operating means for said cutting means engageable with the prime motor and adapted to discontinuously operate said cutting means, and means engageable with

the cutting means and with the clutch and adapted to move the clutch into operative position substantially during the inoperative position of the cutting means.

4. In a cutting machine in combination, a support, a saddle reciprocable on the support for the material, a prime motor, driving and feeding means engageable with the saddle and adapted to reciprocate the same and operatively connected to the prime motor, a clutch member on said driving means, cutting means for the material, operating means for said cutting means engageable with the prime motor and adapted to discontinuously operate said cutting means, means engageable with the cutting means and with the clutch and adapted to move the clutch into operative position substantially during the inoperative position of the cutting means, coupling and uncoupling means intermediate the prime motor and cutting means and means operatively engageable with the cutting means and adapted to control and operate said coupling and uncoupling means.

5. In a cutting machine in combination, a support, a saddle for the material reciprocable on the support, a prime motor, driving and feeding means engageable with the saddle and adapted to reciprocate the same and operatively connected to the prime motor, a clutch member on said driving and feeding means, cutting means for the material and operating means for the cutting means engageable with the prime motor and adapted to discontinuously operate said cutting means, operating means for the clutch engageable with the cutting means and additional clutch-operating means engageable with the saddle, coupling and uncoupling means intermediate the prime motor and cutting means and means operatively engageable with the cutting means and adapted to control and operate said coupling and uncoupling means.

6. In a cutting machine in combination, a support, a saddle for feeding the material reciprocable on the support, a prime motor, driving and feeding means engageable with the saddle and adapted to reciprocate the same and operatively connected to the prime motor, a clutch member on said driving and feeding means, cutting means for the material and operating means for the cutting means engageable with the prime motor, operating means for the clutch engageable with the cutting means and additional clutch-operating means engageable with the saddle, coupling and uncoupling means intermediate the prime motor and cutting means and means operatively engageable with the cutting means adapted to control and operate said coupling and uncoupling means and additional operating means for said coupling and uncoupling means operatively engageable with the cutting means, and means engageable with the saddle.

7. In a cutting machine in combination, a support, a saddle for feeding the material reciprocable on the support, a prime motor, driving means engageable with the saddle and adapted to reciprocate the same and operatively connected to the prime motor, a clutch member on said driving means, operating means for the clutch member, cutting means for the material engageable with the prime motor and adapted to discontinuously operate said cutting means, coupling and uncoupling means intermediate the prime motor and cutting means operatively engageable with the cutting means and operating means for the coupling and uncoupling means operatively engageable with the saddle in certain positions thereof. 70
8. In a cutting machine in combination, a support, a feeding member for the material reciprocable on the support, a prime motor, a rocking member operatively connected to the prime motor adjustable link connection between the rocking member and the feeding member, means on the support for converting the rocking movement into reciprocating movement of the feeding member, additional manually operable moving means for the feeding member and discontinuously operated cutting means for the material. 80
9. In a cutting machine in combination, a support, a reciprocable feeder on the support for the material, a prime motor, a rocking member operatively connected to the prime motor, a rotating member and adjustable link connection between said member and the rocking member, coupling means between the rotating member and the feeder, means for adjusting and regulating the said coupling means, a clutch intermediate the rocking member and the prime motor, operating means for said clutch and cutting means for the material. 90
10. In a cutting machine in combination, a support, a reciprocable feeder on the support for the material, a prime motor, a rocking member operatively connected to the prime motor, a driving wheel on the support and operatively connected to the feeder, a rotating member and adjustable link connection thereof with the rocking member, coupling means between the rotating member and the driving wheel for turning the wheel in one direction only, a clutch intermediate the rocking member and the prime motor, operating means for said clutch and cutting means for the material. 100
11. In a cutting machine in combination, a support, a reciprocable feeder on the support for the material, a prime motor, a rocking member operatively connected to the prime motor, a driving wheel operatively connected to the feeder and adapted for manual operation, a rotating member and link connection thereof with the rocking member, coupling means between the rotating member and the driving wheel, a reversing gear operatively connected to the prime motor, means to change the direction of rotation of said gear and rockable driving means connected to said gear and engageable with the driving wheel and cutting means for the material. 110
12. In a cutting machine in combination, a support, a reciprocable feeder on the support for the material, a prime motor, a rocking member operatively connected to the prime motor, a driving wheel operatively connected to the feeder and adapted for manual operation, a rotating member and link connection thereof with the rocking member, releasable coupling means between the rotating member and the driving wheel, braking means operatively associated with the coupling means and with the rotating member and adapted to allow rotation of the latter in one direction only, a reversing gear operatively connected to the prime motor, means to change the direction of rotation of said gear when the coupling means is released, rockable driving means connected to said gear and engageable with the rotating member, an operating member connected to the coupling means and adapted to rock the driving means into and out of engaging position, and cutting means for the material. 120
13. In a cutting machine in combination, a support, a movable feeder on the support for the material, a prime motor and coupling means between the motor and the movable feeder, cutting means for the material and operating means for the cutting means connected to the prime motor and adapted to discontinuously operate the cutting means, a coupling member intermediate the motor and the cutting means, spring-actuated lever connection between the cutting means and said coupling member and operating means for the spring-actuated lever connection. 130
14. In a cutting machine in combination, a support, a movable feeder on the support for the material, a prime motor and coupling and uncoupling means between the motor and the movable feeder, cutting means for the material and operating means for the cutting means connected to the prime motor and adapted to discontinuously operate the cutting means, a coupling member intermediate the motor and the cutting means, spring-actuated lever connection between the cutting means and said coupling member, a spring actuated lever engageable with said lever connection and operatively connected to the coupling and uncoupling means for the feeder. 140
15. In a cutting machine in combination, a support, a feeder on the support for the material, a prime motor, moving means for the feeder operated by said motor, a spring-actuated clutch-member intermediate the moving means and the prime motor, cutting means for the material, link-members en- 150

- gageable with the clutch, and cam members operatively engageable with the link-members.
16. In a cutting machine in combination, a support, a movable feeder on the support for the material, a prime motor, moving means for the feeder operated by the motor, a spring-actuated clutch intermediate the moving means and the motor, cutting means for the material, two differently-sized coaxially disposed cams, link-members operatively engageable with the clutch, and operatively engageable with either of the cams.
17. In a cutting machine in combination, a support, a movable feeder on the support for the material to be treated, a prime motor, moving means for the feeder, operatively connected to the motor, a spring-actuated clutch intermediate the moving means and the motor, cutting means for the material operated by the motor, two differently-sized coaxially disposed cams, link-members operatively engageable with the clutch and operatively engageable with either of the cams, and additional manually operated actuating means on said link-members.
18. In a paper cutting machine in combination, a support, a movable feeder on the support for the material, a prime motor, cutting means for the material operatively connected to the prime motor, coupling and uncoupling means intermediate the motor and the cutting means, spring-actuated engaging and disengaging means for the coupling and uncoupling means, means to manually operate the engaging and disengaging means, and a lever acting as a catch engageable with the engaging and disengaging means and adapted to secure the same in the coupling position.
19. In a cutting machine in combination, a support, a movable feeder on the support for the material, a prime motor, an operative connection between the feeder and the motor, and a spring-actuated clutch on said operative connection, cutting means for the material, coupling and uncoupling means connecting the motor to the cutting means, operating links engageable with the clutch, and operating links engageable with the coupling means for the cutting means, and means on the feeder to engage with the operating links for the clutch and for the coupling means of the cutting means.
20. In a paper cutting machine in combination, a support, a movable feeder on the support for the material, a prime motor, cutting means for the material operatively connected to the prime motor, coupling and uncoupling means intermediate the motor and the cutting means, spring-actuated engaging and disengaging means for the coupling and uncoupling means, and a spring-influenced clutch adapted for engagement with the engaging and disengaging means and adapted to secure the same in the coupling position.
21. A saddle drive in cutting machines for paper, cardboard and the like, including in combination with a saddle operating wheel, a conical toothed gear reversing drive, a conical coupling, and a hand lever for the purpose of obtaining a slow or intermittent feed of the saddle operating wheel and a consequent accurate adjustment thereof.
22. A saddle drive as claimed in claim 21, wherein means is provided for automatically bringing the hand lever into its intermediate position to effect uncoupling, substantially as and for the purposes set forth.
- In testimony whereof I affix my signature.
